UNITED STATES PATENT OFFICE

ARTHUR A. SCHUPP, OF SAGINAW, MICHIGAN, ASSIGNOR TO FREDERICKSEN COMPANY, OF SAGINAW, MICHIGAN, A CORPORATION OF MICHIGAN.

MEANS FOR SECURING ANTI-FRICTION PADS TO LEAF SPRINGS

Application filed December 5, 1928. Serial No. 323,836.

This invention relates to leaf springs of the kind whose overlapping leaves are separated near their free ends by intervening pads of anti-friction material, for example, 5 plates or disks or cast bronze or other suitable metal for rendering the springs easier working and for preventing wear and noise when the springs are in use.

My invention is found in a novel mode of 10 attaching the anti-friction pad to the spring leaf.

The objects of the improvement are to reduce the cost of manufacture by employing a flat disk pad having an aperture instead 15 of one formed with a projecting stem member as heretofore; to avoid making an aperture in the spring leaf, thereby weakening it as heretofore; and the strengthen the leaf by striking or pressing up a part of its face 20 to form a boss that acts as an anchorage for securing the disk to the spring, the striking up operation being no more costly than the usual hole punching operation.

Another object is to provide a boss having 25 sharp peripheral edges and being slightly larger than the hole in the disk so that the disk, when forced onto the boss, will have the walls of its bore scraped by and hence accurately fitted to the boss. Moreover, 30 metal scrapings produced by that operation collect at the face of the boss and consequently can not become packed between the spring and the disk to prevent proper seating of the disk, as often occurs when the projecting 35 stem of a soft metal disk is forced into a hole in the spring leaf, a mode of fastening which has heretofore been employed.

With the foregoing and certain other objects in view, which will appear later in the 40 specification, my invention comprises the devices described and claimed and the equivalents thereof.

In the drawings Fig. 1 is a side view of a leaf spring to which my invention is adapted to be applied.

Fig. 2 is an enlarged view, partly in section, showing the boss and disk detached.

Fig. 3 is a similar view assembled.

The leaf spring may be of any appropriate 50 type, usually a plurality of overlapping

leaves 1, 2, spaced apart near their ends by intervening pads 3 of anti-friction metal. In applying my invention to a pad-and-spring construction of this kind I provide a boss 4, shown in Figs. 2 and 3, projecting 55 a short distance outwardly from a face of the spring leaf, say, about three sixty-fourths inch.

The other face of the leaf, opposite the boss, is formed with a shallow depression 8, 60 made dish-like with gradually sloping edges, indicated by dotted lines in Fig. 2, in order that the back of a leaf shall present no sunken places in which a projection on an adjacent spring might possibly catch and thereby 65 hamper the free sliding movement of the leaves one upon another.

The boss 4 is preferably cylindric in shape, but may be square, polygonal or of any other desired contour. It is preferably formed by 70 striking up the material of the spring over an area, say, one half inch diameter, while forcing the material so displaced into a suitable forming die that imparts to the boss straight walls 5, that is to say, walls that 75 possess substantially sharp peripheral edges 6 around the face of the boss and a sharp corner 7 at its junction with the spring leaf.

As has been stated, pad 3 may be a thin circular or rectangular plate or washer of 80 bronze, and preferably is appropriately apertured at 3a to suit the shape, size and location of the boss 4.

The aperture 3a may extend clear through the pad 3, or only part way through it, but 85 in any event the depth of the aperture and the thickness of the pad are both greater than the thickness of the boss 4 so the boss when in use can not contact with the face of an adjacent spring leaf. Preferably the size 90 of the aperture 3a is slightly less than the cross sectional size of the boss. In other words, the boss is made slightly over-size for the aperture. The purpose of this is to keep the pads in place while assembling a number 95 of leaves to form the complete spring structure.

When the pad is forced into place upon the boss it seats snugly against the leaf face 100 while the over-sized boss with its sharply

defined edges 6 and parallel walls 5 makes a place for itself in the bore 3a and fits very tightly therein, as in press-fit relation.

Any small metal particles 9 which the edges 6 of the boss shear from the walls of the aperture 3a remain in the aperture and can not do any harm.

Heretofore pads have been employed having projecting shanks driven into holes in the spring and difficulty has been experienced because the metal scraped from the stem necessarily lodged between the face of the spring and the face of the pad, preventing the pad from seating fairly against the spring. The arrangement herein described avoids that difficulty by keeping the metal scrapings away from the contacting faces of leaf 1 and pad 3.

In operation the anti-friction pad applied in the manner described remains in place until its face is worn down to the end of the boss, after which it may be replaced. The aperture 3a forms also an oil pocket that aids in keeping the face of the pad lubricated during its back-and-forth rubbing movement.

Having thus described my invention, what I claim and desire to secure by Letters Patent is:

30 1. In a leaf spring whose leaves are separated near their free ends by intervening pads of anti-friction material, means for fastening a pad to a leaf comprising a boss struck from the material of the spring and projecting from a face thereof, said boss disc-shaped with abrupt peripheral edges at its disk face and likewise at the junction of the boss with the face of the spring, and a centrally apertured pad of anti-friction material which is of greater thickness than the boss and is received thereon in force-fitting relation thereto.

45 2. In a leaf spring whose leaves are separated near their free ends by intervening pads of anti-friction material, means for fastening a pad to a spring comprising a boss projecting from a face of the spring, said boss formed with sharply defined peripheral edges at its outer face and likewise at the junction of the boss with the face of the spring, and a pad of anti-friction material of greater thickness than the boss apertured to receive said boss.

55 3. A leaf spring having a boss projecting outwardly from a face thereof and a substantially flat pad of anti-friction material of greater thickness than the boss and formed with an aperture receiving said boss in press-fit relation, for the purpose set forth.

60 4. A spring leaf having a boss projecting outwardly from a face thereof, a pad of anti-friction material seated against said leaf face and formed with an aperture receiving said boss, the depth of said aperture

greater than the thickness of said boss, and the size of the aperture normally slightly less than the cross-sectional size of the boss.

In testimony whereof, I affix my signature.

ARTHUR A. SCHUPP.
